CLAIM

The ornamental design for a valve control module, as shown
and described.

DESCRIPTION

FIG. 1 is a perspective view of a valve control module in
accordance with the present design;

FIG. 2 is a front view of the valve control module of FIG. 1;
FIG. 3 is a left side view of the valve control module of FIG.
1;

FIG. 4 is a right side view of the valve control module of FIG.
1;

FIG. 5 is a top plan view of the valve control module of FIG.
1; and

FIG. 6 is a bottom plan view of the valve control module of
FIG. 1.

The broken lines showing in the figures are for the purpose of
illustrating portions of the valve control module and form no
part of the claimed design.
